COOLING APPARATUS

Ernest F. Stalcup, Rutledge, Pa., assignor to
Westinghouse Electric & Manufacturing Com-
pany, East Pittsburgh, Pa., a corporation of
Pennsylvania

Application October 20, 1933, Serial No. 694,511

22 Claims. (Cl. 62—152)

My invention relates to refrigeration apparatus and particularly to the type generally known as steam jet refrigeration apparatus, and it has for an object to improve the operation thereof.

5 A further object of my invention is to provide novel means for controlling the operation of the ejector of a steam jet refrigerating system so that communication between the evaporating chamber and the ejector is permitted only during 10 periods of normal operation of the ejector.

In refrigeration apparatus of the steam jet type, cooling of liquid is effected in a closed chamber by withdrawing vapor and non-condensable gases therefrom, which is effected by 15 an ejector motivated by steam or other condensable vapor. The vapor exhausted from the ejector is condensed in a condenser in which it is brought into heat exchanging relation with a cooling medium, usually water. As a low pressure 20 is maintained in the chamber by the ejector, the liquid admitted thereto will vaporize at a low temperature; the latent heat of vaporization of the portion of the liquid vaporized being abstracted from the body of liquid in the chamber 25 so that its temperature is substantially reduced.

It is desirable in the operation of equipment of this kind that the ejector be isolated from the evaporating chamber at times when its suction pressure is above the pressure to be maintained 30 in the chamber. This condition is present during starting periods, and may also result when faulty operation of the ejector occurs.

The necessity of isolating the ejector is found particularly in apparatus embodying a plurality 35 of ejectors, one or more of said ejectors being shut down for partial loads. In such case, reverse flow of vapor from the condenser to the evaporating chamber takes place through the ejector not in operation, unless communication 40 therethrough is cut off.

It is a particular object of my invention to provide control means operating to prevent reverse flow of vapor through the ejector by cutting off communication therethrough at the proper time.

45 In accordance with my invention, I provide a valve between the inlet of the ejector and the evaporating chamber, which valve is preferably operated by fluid under pressure. Means responsive to the pressure of vapor between said valve 50 and the inlet of the ejector is provided for controlling the operation of the valve, so that the valve is opened when the pressure in the ejector inlet has been reduced to a predetermined amount. Furthermore, the means referred to 55 may be made responsive, differentially, to the

pressure in the ejector inlet and the pressure in the ejector outlet, whereby the valve is moved to a closed position when the difference in pressures in the inlet of the ejector and in the outlet thereof fall below a predetermined value. Alternatively, the valve may be operated in response to the temperature of the vapor in the ejector inlet so that it is open when the temperature is low and is closed when, for any reason, a reverse flow of steam from the condenser increases the temperature in the inlet of the ejector.

The above and other objects are effected by my invention, as will be apparent from the following description and claims taken in connection with the accompanying drawing forming a part of this application, in which:

Fig. 1 is a diagrammatic view, showing a steam jet refrigerating system arranged in accordance with my invention;

Fig. 2 is a sectional view of a detail included in my invention;

Fig. 3 is a fragmentary diagrammatic view of a modification.

Referring now to Figs. 1 and 2 of the drawing, I show, in Fig. 1, an evaporating chamber 10 having an inlet 11 for the admission of liquid to be cooled and an outlet 12 for liquid which has been cooled. The latter is connected to a conduit 13 provided with a pump 14 for conveying the cooled liquid to a point of use. The chamber 10 is in communication with the inlet connection 5 of an ejector 6, which includes a nozzle chamber 7 and a converging-diverging conduit portion 8. It is also connected through a valve 16 to the inlet connection 17 of a steam ejector 18, the latter comprising a nozzle chamber 19 and a converging-diverging conduit portion 20.

The exhaust ends of the ejectors 6 and 18 are connected to the vapor inlet 21 of a condenser 22 having connections 23 and 24 for the admission and discharge of a cooling medium, preferably water. The condenser 22 is provided with a connection 25 through which condensate and non-condensable gases may be withdrawn.

The ejectors 6 and 18 are motivated by steam or other suitable vapor which is condensable at the pressure at which it is exhausted from the ejector. The steam is supplied to the ejector 18 from any convenient source through a conduit 26 having a valve 27 connected therein. Motivating steam for the ejector 6 is controlled by the valve 9.

In accordance with the present invention, means are provided for isolating the ejector 18 from the evaporating chamber 10, automatically,

when the pressure in the inlet connection 17 rises above a predetermined value, such isolating means being shown in Figs. 1 and 2 as comprising a pressure responsive device 28, a pilot valve structure 29 operated thereby, and a motor device 31 operatively connected to the valve 16.

The motor device 31 includes a cylinder 32 having a piston 33 slidably mounted therein. Movement of the piston 33 is transmitted to the valve 16 by means of a piston rod 34. With the piston 33 in the position shown in Fig. 1, the valve 16 will be in its closed position and communication between the ejector inlet connection 17 and the evaporating chamber 10 will be interrupted.

The pressure responsive device 28 and the pilot valve 29 are best shown in Fig. 2. The device 28 includes a casing 35 divided into chambers 36 and 37 by a diaphragm 38. The chamber 36 is connected by means of a conduit 39 to the inlet connection 17 and the chamber 37 is preferably connected to the inlet 21 of the condenser 22 by means of a conduit 41. The diaphragm 38 is connected by means of a stem 42 to a valve 43, which is the movable element of the pilot valve structure 29. The latter includes also a cylinder 44 having heads 45 and 46. The structure 29 is secured in spaced relation to the pressure responsive device 28 by rods 47 and stuffing boxes 48 and 49 are preferably provided for the stem 42 where it passes through the casing 35 and cylinder head 45, respectively.

The valve 43 has spaced piston portions 51 and 52 formed thereon, which portions cooperate with ports 53 and 54 in the cylinder 44. The port 53 communicates with the portion of cylinder 32 on the upper side of the piston 33 by means of conduit 55 and the port 54 communicates with the portion of the cylinder 32 on the lower side of the piston 33 by means of conduit 56. A port 57 is formed in cylinder 44, and is in communication at all times with the space between the piston portions 51 and 52 and with a conduit 58 connected to a source of fluid pressure (not shown). A conduit 59 communicates with the ends of the cylinder 44 for conveying fluid therefrom to a point of discharge when the valve 43 is moved from one position to another.

During periods when the ejector 18 is shut down, or at any time when the pressure in the inlet connection 17 is as great as the pressure in the connection 21, the diaphragm 38 and valve 43 will be in their right hand positions as shown in Fig. 2. They are biased to this position by a spring 61, the bias of which may be adjusted conveniently by an adjusting screw 62 threaded in the casing 35 and supporting one end of the spring 61. A stuffing box 63 may be provided for the screw 62 to prevent ingress of air into the chamber 36.

Assuming the apparatus to be shut down, the various elements will be in the positions shown in the drawing. As the valve 43 is in its extreme right hand position, pressure from the conduit 58 is impressed on the underside of the piston 33 through the ports 57 and 54 and the conduit 56 so that the valve 16 is closed. Pressure on the upper side of the piston 33 will be relieved through the conduit 55 and the port 53, to the discharge conduit 59.

As the valve 9 is opened, motivating steam is supplied to the nozzles of the ejector 6 so that vapor and non-condensable gases in the chamber 10 are entrained thereby and the mixture is discharged into the condenser 22. The pressure in the chamber 10 is reduced to a low value by the

ejector 6 and cooling of the liquid entering through inlet 11, is effected by evaporation. The cooled liquid is conveyed to a point of use by the pump 14.

As the demand for refrigeration increases the steam valve 27 is opened to admit motivating steam to the ejector 18. Vapor and non-condensable gases in the inlet connection 17 are entrained by the ejector 18 and are discharged into the condenser 22. The vapor discharged into the condenser 22 by both ejectors is condensed therein and the condensate and non-condensable gases may be withdrawn from the condenser 22 by any convenient means through the connection 25.

The pressure in the connection 17, conduit 39 and chamber 36 will drop due to the entrainment of vapor and gases by the ejector 18 and, when the pressure difference in the chambers 36 and 37 reaches a predetermined amount, as determined by the setting of the adjusting screw 62, the bias of the spring 61 will be overcome and the diaphragm 38, stem 42, and valve 43 will move to the left. The adjustment of the screw 62 will be such that movement of the valve 43 is effected when the pressure in chamber 36 is substantially equal to the pressure in chamber 10. Pressure from supply conduit 58 will now be admitted to the cylinder 32 above the piston 33 through ports 57 and 53 and conduit 55. At the same time, pressure from below the piston 33 will be relieved through the conduit 56, port 54 to the discharge conduit 59. The valve 16 will, therefore, be opened to establish communication between the inlet connection 17 of the ejector 18 and the evaporating chamber 10.

When the demand for refrigeration is reduced and the steam valve 27 is closed, the pressure in the condenser 22 and the inlet connection 17 equalize through the ejector 18. As the pressures in the chambers 36 and 37 become of substantially equal value, the bias of the spring 61 moves the valve 43 to the position shown in the drawing. The pressure in the cylinder 32 above the piston 33 is relieved through the conduit 55 and port 53 to the discharge conduit 59 and pressure from the supply conduit 58 is admitted to the cylinder 32 beneath the piston 33 through ports 57 and 54 and conduit 56. The piston 33 moves upwardly to close valve 16 so that the ejector 18 is isolated from the evaporating chamber. The ejector 18 will now be in its inoperative or "shut down" position.

The foregoing description relates to the normal operation of my improved refrigerating apparatus when started and stopped. It will be apparent, however, that operation of the valve 16 in a closing direction will accompany any faulty operation of the ejector 18 which will cause a rise in pressure in the inlet connection 17. For example, in the event that the steam jet would become disrupted, for any reason, the tendency for steam to flow back into the evaporating chamber 10 would be prevented, as a rise in pressure in the inlet connection 17 and, consequently, in the chamber 36 would result. When the difference in pressures in chambers 36 and 47 drops to a predetermined amount determined by the setting of the adjusting screw 62, the spring 61 would move the stem 42 and valve 43 to the position shown in the drawing and closing the valve 16 would result in the manner previously described.

It will be apparent that pressure sources other than the condenser 22 may be utilized for chamber 37, but I prefer to use the pressure of the condenser as it is maintained substantially con-

stant at all times, so that a more accurate adjustment of the pressure responsive device 28 may be obtained.

It will be understood that the ejector 6, and 5 any additional ejector, may also be equipped with a valve between its inlet and the evaporating chamber 10, and also the controlling means therefor, in the same manner as the ejector 18. In this event, either ejector would be isolated 10 from the chamber 10 when inactive.

Reference will now be had to Fig. 3 in which I have shown means responsive to the temperature of the vapor in the ejector inlet for operating the valve 16. A thermostat 70 preferably includes a bulb 71 subjected to the temperature of the vapor in the inlet connection 17' of the ejector 18' and an expansible bellows 72 connected to the bulb 71 by a tube 73. The bulb 71, tube 73 and bellows 72 define a closed chamber in which a volatile fluid is enclosed so that with an increase of temperature in the inlet connection 17' the bellows 72 will expand and conversely with a decrease in temperature the bellows 72 will contract. Movement of the bellows 72 is transmitted to the 25 valve 43' of the pilot valve structure 29' by means of a stem 42'.

When the ejector 18' is shut down, the bulb 71 is subjected to the temperature of the vapor at the discharge end thereof as the ejector forms 30 an equalizing passage between its inlet connection 17' and its discharge end. As this temperature is relatively high, the bellows 72 will be expanded and the valve 43' will be in its lowermost position as shown. As the construction and operation of the pilot valve structure 29' and the valve operating motor device 31' are the same as disclosed in Figs. 1 and 2, no detailed description of them will be necessary and the operation only will be described. In this position of the valve 40 43', pressure from the conduit 58' will be impressed on the under side of the piston 33' through conduit 56'. Pressure on the upper side of the piston 33' will be relieved through conduit 55', valve structure 29', and the discharge conduit 59'. The valve 16 is therefore closed.

As steam is admitted to the nozzles 74 of the ejector 18', vapor and non-condensable gases in the inlet connection 17' will be entrained by the steam jet so that the pressure and temperature 50 of the vapor in the connection 17' will be substantially reduced. The bellows 72 contracts to move the valve 43' to its uppermost position. Pressure from the under side of the piston 33' is relieved through conduit 56' to the discharge 55 conduit 59' and pressure from the supply conduit 58' is impressed on the upper side of the piston 33' through conduit 55'. The valve 16 opens to establish communication between the inlet connection 17' and the chamber 10.

60 As the supply of motivating fluid to the nozzles 74 is discontinued, the relatively high temperature vapor from the discharge end of the ejector 18' will back into the connection 17' and the thermostat 70 will then operate to close the valve 16 as described. It will be apparent that closure 65 of the valve 16 will also accompany any breakdown in the jet during operation as the relatively warm vapor will flow back into the connection 17' where the thermostat bulb 71 is located.

70 From the foregoing, it will be seen that I have provided an improved steam jet refrigerating system in which communication between the inlet 75 of an ejector and the evaporating chamber is established only when a condition in the ejector

inlet is of a predetermined and desirable value, which value may be adjusted at will.

While I have shown my invention in two forms, it will be obvious to those skilled in the art that it is not so limited, but is susceptible of various 5 other changes and modifications without departing from the spirit thereof, and I desire, therefore, that only such limitations shall be placed thereupon as are imposed by the prior art or as are specifically set forth in the appended claims. 10

What I claim is:

1. In vapor jet refrigeration apparatus, the combination of an evaporating chamber, means for admitting liquid to said chamber, an ejector for withdrawing vapor from the evaporating 15 chamber to effect partial evaporation and cooling of the liquid therein, and means responsive to a condition effected by the ejecting action of the ejector for establishing communication between said ejector and evaporating chamber. 20

2. In vapor jet refrigeration apparatus, the combination of an evaporating chamber, means for admitting liquid to be partially evaporated and cooled to said chamber, an ejector for withdrawing vapor from the chamber, means forming 25 a passage between said chamber and said ejector for conducting the withdrawn vapor to the ejector, and means for shutting off flow through the passage in response to a predetermined maximum temperature in the passage. 30

3. In vapor jet refrigeration apparatus, the combination of an evaporating chamber, means for admitting liquid to be partially evaporated and cooled to said chamber, an ejector for withdrawing vapor from the chamber, means forming 35 a passage between said chamber and said ejector for conducting the withdrawn vapor to the ejector, and means for shutting off flow through the passage in response to a predetermined maximum absolute pressure in the passage. 40

4. In vapor jet refrigeration apparatus, the combination of an evaporating chamber, means for admitting liquid to be partially evaporated and cooled to said chamber, an ejector for withdrawing vapor from the chamber, means forming 45 a passage between said chamber and said ejector for conducting the withdrawn vapor to the ejector, a valve in said passage, and means for operating said valve in accordance with pressure conditions in the passage on the ejector side 50 of the valve.

5. In vapor jet refrigeration apparatus, the combination of an evaporating chamber, means for admitting liquid to be partially evaporated and cooled to said chamber, an ejector having an 55 inlet for withdrawing vapor from the chamber, means for conveying vapor discharged by the ejector, and means differentially responsive to pressures in said inlet and said conveying means for controlling the flow of vapor from the chamber to the ejector. 60

6. In vapor jet refrigeration apparatus, the combination of an evaporating chamber, means for admitting liquid to be partially evaporated and cooled to said chamber, an ejector for withdrawing vapor from the chamber, means forming 65 a passage between said chamber and said ejector for conducting the withdrawn vapor to the ejector, means for condensing the vapor discharged by the ejector, and means for controlling the flow of 70 vapor from the chamber to the passage in accordance with conditions in the passage and the condensing means.

7. In vapor jet refrigeration apparatus, the combination of an evaporating chamber, means 75

- for admitting liquid to be partially evaporated and cooled to said chamber, an ejector for withdrawing vapor from the chamber, means forming a passage between said chamber and said 5 ejector for conducting the withdrawn vapor to the ejector, means for condensing the vapor discharged by the ejector, and means for controlling the flow of vapor from the chamber to the passage in accordance with pressure differentials between the passage and the condensing means. 10
8. In vapor jet refrigeration apparatus, the combination of an evaporating chamber, means for admitting liquid to be partially evaporated and cooled to said chamber, an ejector for withdrawing vapor from the chamber, means forming a passage between said chamber and said 15 ejector, for conducting the withdrawn vapor to the ejector, means for condensing the vapor discharged by the ejector, and means for controlling the flow of vapor from the chamber to the passage in accordance with pressure differentials between the passage and the condensing means, and means for adjusting said pressure differentials. 20
9. In vapor jet refrigeration apparatus, the combination of an evaporating chamber, means for admitting liquid to be partially evaporated and cooled to said chamber, an ejector having an inlet for withdrawing vapor from the chamber, a valve for controlling the flow of vapor from the chamber to the inlet of said ejector, a condenser for condensing vapor discharged by the ejector, and a device differentially responsive to pressures in the condenser and said inlet for operating said 30 valve. 35
10. In vapor jet refrigeration apparatus, the combination of an evaporating chamber, means for admitting liquid to be partially evaporated and cooled to said chamber, an ejector having an inlet for withdrawing vapor from the chamber, a valve for controlling the flow of vapor from the chamber to said ejector, a condenser for condensing vapor discharged by the ejector, and a device differentially responsive to pressures in the condenser and said inlet for operating said valve, and means for adjusting the pressure differential at which said device operates. 40
11. In vapor jet refrigeration apparatus, the combination of an evaporating chamber, means for admitting liquid to be partially evaporated and cooled to said chamber, an ejector having an inlet for withdrawing vapor from said chamber, a valve for controlling the flow of vapor from the chamber to the inlet of said ejector, a condenser for condensing vapor discharged by the ejector, and a device, differentially responsive to the discharge pressure of said ejector and the pressure in said inlet, for controlling the operation of the valve. 50
12. In vapor jet refrigeration apparatus, the combination of an evaporating chamber, means for admitting liquid to be partially evaporated and cooled to said chamber, an ejector, a conduit between said ejector and said chamber for conveying vapor and other non-condensable gases from the chamber to the ejector, means for conveying vapor and non-condensable gases discharged by the ejector, a valve in said conduit for controlling the passage of gases and vapor from the chamber to the ejector, and a device differentially responsive to pressures in said conduit and said conveying means for controlling the operation of the valve; said device including hydraulic means for opening and closing the valve, a control valve for controlling the flow of fluid to said hydraulic means, a casing, a diaphragm disposed within the casing for actuating said control valve, means providing communication between said casing on one side of the diaphragm with said conduit, and second means providing communication between said casing on the other side of the diaphragm with said conveying means. 5
13. In refrigeration apparatus, the combination of an evaporating chamber, means for admitting liquid to said chamber for partial evaporation and cooling, a fluid translating device for withdrawing vapor from the chamber, a conduit for conveying said withdrawn vapor, means for conveying vapor discharged by the fluid translating device, a valve disposed between said conduit and the chamber, and means differentially responsive to the pressure in said conduit and the pressure in said conveying means for operating said valve. 10
14. In refrigeration apparatus, the combination of an evaporating chamber, means for admitting liquid to said chamber for partial evaporation and cooling, a fluid translating device for withdrawing vapor from the chamber, a conduit for conveying said withdrawn vapor, a valve between said conduit and said chamber, a condenser, means for conveying vapor discharged by the fluid translating device to the condenser, and means differentially responsive to conditions in said conduit and said conveying means for operating said valve. 20
15. In vapor jet refrigeration apparatus, the combination of an evaporating chamber, means for admitting liquid to be partially evaporated and cooled to said chamber, an ejector for withdrawing vapor from the chamber, means forming a passage between said chamber and said ejector for conducting the withdrawn vapor to the ejector, and means for regulating the flow of vapor from the chamber to the passage in accordance with the temperature in the passage. 30
16. In vapor jet refrigeration apparatus, the combination of an evaporating chamber, means for admitting liquid to be partially evaporated and cooled to said chamber, an ejector having nozzles for withdrawing vapor from the chamber, means forming a passage between said chamber and said ejector for conducting the withdrawn vapor to the ejector, a valve in said passage and means responsive to the temperature of the vapor adjacent the nozzles for operating 40 said valve. 45
17. In refrigeration apparatus, the combination of an evaporating chamber, means for admitting liquid for partial evaporation and cooling to said chamber, a fluid translating device for withdrawing vapor and non-condensable gases from the chamber, means forming a passage from the chamber to the translating device, means for controlling the flow of gases and vapor from the chamber to the passage and means responsive to the temperature of the vapor in said 50 passage for operating said controlling means. 60
18. In vapor jet refrigerating apparatus, the combination of an evaporating chamber, an ejector for withdrawing vapor from said chamber to effect cooling by evaporation of liquid therein, a valve controlling communication between the evaporating chamber and the ejector, and means responsive to a condition effected by the ejecting action of the ejector for opening said valve and 65 responsive to a condition occurring upon absence or failure of ejecting action of the ejector for closing said valve. 70
19. In vapor jet refrigerating apparatus, the combination of an evaporating chamber, an ejec- 75

tor having nozzles for withdrawing vapor from said chamber to effect cooling by evaporation of liquid therein, means for supplying motive fluid to said nozzles, a valve controlling communication between the evaporating chamber and the ejector, and means responsive to a condition of the ejector indicating that motive fluid from the ejector nozzles is flowing to the evaporating chamber for closing said valve.

- 10 20. In vapor jet refrigerating apparatus, the combination of an evaporating chamber, an ejector connected to said chamber for withdrawing vapor therefrom to effect cooling by evaporation of liquid, and means, responsive to a predetermined maximum temperature in the space from which said ejector withdraws vapor indicating flow of motive fluid into said space, for preventing further heating of said evaporating chamber by said motive fluid.
- 15 21. In vapor jet refrigerating apparatus, the combination of an evaporating chamber, an ejector connected to said chamber for withdrawing vapor therefrom to effect cooling by evaporation of liquid, and means, responsive to a condition of the ejector indicating that motive fluid from the ejector nozzles is flowing to the evaporating chamber for closing said valve.
- 20 22. In vapor jet refrigerating apparatus, the combination of an evaporating chamber, an ejector connected to said chamber for withdrawing vapor therefrom to effect cooling by evaporation of liquid, and means, responsive to a condition of the ejector indicating that motive fluid from the ejector nozzles is flowing to the evaporating chamber for closing said valve.

tor connected to said chamber for withdrawing vapor therefrom to effect cooling by evaporation of liquid, a valve for controlling communication between said chamber and said ejector, and means, responsive to a predetermined maximum temperature in the space from which said ejector withdraws vapor indicating flow of motive fluid into said space, for closing said valve to prevent further heating of said evaporating chamber by said motive fluid.

22. In vapor jet refrigerating apparatus, the combination of an evaporating chamber, an ejector connected to said chamber for withdrawing vapor therefrom to effect cooling by evaporation of liquid, and means, responsive to a condition of the ejector indicating that motive fluid from the ejector nozzles is flowing to the evaporating chamber for closing said valve.

ERNEST F. STALCUP. 20
